[57] ABSTRACT

The failure state, due to disconnection or grounding of resistors connected in parallel, is checked in such a way that diodes are connected in series, respectively between the resistors and a common terminal for the parallel connection. A check signal is supplied to the other common terminal for the parallel connection, and the signals appearing at the connection points between the resistors and the diode are compared with the supplied check signal by using a logic circuit such as an AND gate.

FAILURE CHECK CIRCUIT

BACKGROUND OF THE INVENTION

This invention relates to a failure checking circuit to detect an abnormal or state of failure in which at least one circuit element is open circuited or grounded comprising a plurality of circuit elements which are connected in parallel. This invention particularly relates to a circuit for checking a failure due to disconnection or short-circuiting of elements in a firing circuit system for the protection of occupants of a vehicle in the event of a crash.

Recently, there has been proposed and developed to provide a car with safety means such as an air-bag system or a gas-bag system for restraining the occupants of a vehicle to provide protection for the occupants in the event of a crash. The air-bag system comprises detector means for detecting a crash, high-pressure gas cylinders, air-bags which are quickly enlarged in the crash to restrain the vehicle occupants, and firing means for destroying or removing the valves provided between the high-pressure gas cylinders and the air bags. The firing means comprise circuit elements such as resistors of low resistance, so called "firing balls," which are operated by output signals from a detector means in the event of a crash and fire or explode as a result of the heat which the electric current flowing through the resistors generates. Four to eight of these air-bags are provided in a car and, therefore, four to eight firing means are electrically connected in parallel to the detector means.

Since it is absolutely necessary for this kind of safety means to operate with certainty in the event of a crash, it is always necessary to monitor the existence of a failure in the system and warn the driver of the failure.

In order to check for disconnection or grounding of each circuit element, such as the above-mentioned resistors, each circuit line, including the circuit element, must be electrically isolated as to a check signal other than its own signal, since a plurality of circuit elements, such as resistors, are connected in parallel in the air-bag system. It is also noted that if the mean value of the electric current flowing through a resistor, as the check signal, is large, the heat generated in the resistor might blow up the explosives, whereby the air-bag system might operate and restrain the driver and possibly cause a traffic accident. Therefore, it is necessary to use an electric current having a small mean value, as the failure check signal.

SUMMARY OF THE INVENTION

An object of the present invention is to provide a failure check circuit in which the failure of each circuit element can be separately or independently checked in a circuit with a plurality of circuit elements connected in parallel.

Another object of this invention is to provide a failure check circuit in a circuit comprising a plurality of firing means connected in parallel, for checking the failure state of the firing means without actually operating them.

A further object of this invention is to provide a failure check circuit in a firing circuit comprising a plurality of resistors, having a low resistance, connected in parallel, wherein the mean value of the electric current, flowing through a resistor as a check signal, is small.

Still a further object of this invention is to provide a check system suitable for use in an air-bag protection system for vehicles.

To obtain the above-mentioned objects, the failure check circuit according to the present invention comprises a plurality of serial unit circuits each comprising a circuit element such as resistor and a diode connected in series; connection means for electrically connecting the serial unit circuits in parallel between a first and a second common terminal; signal supply means for supplying an electrical signal to the first common terminal; detecting means for detecting the failure state of the circuit elements having a plurality of input terminals and an output terminal; and connection means for electrically connecting the input terminals respectively with the connection points between the circuit elements and the diodes.

A failure check circuit according to an embodiment of the present invention comprises a plurality of serial unit circuits each comprising a first diode, a circuit element such as resistor and a second diode which are connected in series; and connection means for electrically connecting the serial unit circuits in parallel between a first and a second common terminal. A check signal such as a pulse signal is supplied to the first common terminal and the output signals appearing at the connection points between the circuit elements and the second diodes are checked through a detector for detecting the failure of the circuit elements, and/or wherein check signals such as pulse signals are supplied to the connection points between the first diodes and the circuit elements and an output signal appearing at the second common terminal is checked, through a detector for detecting the failure of the circuit elements.

These and further objects, features and advantages of the present invention will become more obvious from the following description when taken in connection with the accompanying drawings in which:

BRIEF DESCRIPTION OF THE DRAWINGS

FIG. 1 is a circuit diagram of a failure check circuit according to an embodiment of this invention which is applied to an air-bag system; and

FIG. 2 shows waveforms of the output pulse signals of the pulse generator and the frequency dividers which are used in the circuit of FIG. 1.

DESCRIPTION OF THE PREFERRED EMBODIMENT

Referring now to FIG. 1, reference numerals 1 and 2 show terminals which are connected to a power source (not shown), reference letters B₁ to B₄ are circuit elements such as resistors of about 1 to 5 ohms for firing air bags (not shown), reference letters D₁ to D₈ are diodes, reference letters S₁ and S₂ are crash-detect switches comprising mechanical switches which close in the event of a crash of a vehicle and reference letter R is a load resistor of more than 500 kΩ, and wherein the frequency dividers respectively each comprises, for example, a flip-flop circuit. The resistors for firing air bags (hereinafter referred as to fire-resistors B₁ to B₄) are each respectively connected to one end of the diodes D₁ to D₄ through terminals or connection points P₃ to P₆, and the other ends of the diodes D₁ to D₄ are connected together to the crash-detect switch S₁ through the first common connecting terminal P₁. The

other ends of the fire-resistors B_1 to B_4 are connected respectively to each one end of the diodes D_5 to D_8 through terminals or connection points P_7 to P_{10} and the other ends of the diodes D_5 to D_8 are connected to the crash-detect switch S_2 through the second common connecting terminal P_2 . A check signal is supplied from the pulse signal generator to the first common terminal P_1 , to the frequency dividers F_1 to F_4 and to an input terminal of the pulse detector A_2 . Output terminals of the frequency dividers F_1 to F_4 are respectively connected to the connecting terminals or points P_3 to P_6 between the fire-resistors B_1 to B_4 and the diodes D_1 to D_4 . The input terminals of the pulse detector A_1 are connected to the second common terminal P_2 and to each output terminal of the frequency dividers F_1 to F_4 . The input terminals of the pulse detector A_2 are connected to each of the connecting terminals or points P_7 to P_{10} between the fire-resistors B_1 to B_4 and the diodes D_5 to D_8 . These pulse detectors A_1 and A_2 comprise logic circuits, for example, AND circuits in which an output signal appears at the output terminal only when input pulse signals are simultaneously supplied to the input terminals thereof. For example, the detector A_2 operates to cause an output pulse signal to appear at the output terminal thereof only when the pulse signal transmitted from the pulse signal generator PG and the pulse signals transmitted through the connection points P_7 to P_{10} between the fire-resistors B_1 to B_4 and the diodes D_5 to D_8 are simultaneously applied to the input terminals of the detector A_2 . Output terminals of the pulse detectors are connected with alarm circuits (not shown) such as a lamp and a buzzer circuit in order to provide a warning to the driver etc. of an abnormal state in the system.

Referring now to FIG. 2, reference letters V_{PG} , V_{F1} , V_{F2} , V_{F3} , and V_{F4} show waveforms of the output signals from the pulse signal generator PG and frequency dividers F_1 to F_4 , respectively. In the drawing the axis of the abscissa is used to show time t .

The operation of the main circuit as shown in FIG. 1 is briefly explained as follows. Between the terminals 1 and 2, is connected a power source circuit such as a battery and a charged-up condenser, whereby a positive voltage is applied to the terminal 1 in case the diodes D_1 to D_8 are connected with a polarity as shown in FIG. 1. If a crash occurs, the crash-detect switches S_1 and S_2 close or are in the "ON" condition and a large amount of current flows through the fire-resistors B_1 to B_4 in order to operate the air-bag system. Under conditions other than a crash, however, the crash detect switches S_1 and S_2 are open or in the "OFF" state.

In a condition other than a crash, it is always necessary to check whether the fire-resistors B_1 to B_4 are defective or have failed. According to the present invention such a check can be effectively carried out as follows:

1. The normal state of the fire-resistors B_1 to B_4 .

In case all the fire-resistors B_1 to B_4 are in good condition or normally connected, namely, in case none of the fire-resistors B_1 to B_4 is disconnected or grounded, pulse signals appear at all the connection points P_7 to P_{10} between the fire-resistors B_1 to B_4 and the diodes D_5 to D_8 when a pulse signal is applied to the first common terminal P_1 by the pulse generator PG. Therefore to all the input terminals of the detector A_2 pulse signals are simultaneously transmitted and a pulse signal is caused to appear at the output terminal of the detector A_2 . In

this case the alarm or warning circuit may be set in such a way not to operate an alarm or a warning light.

II. An abnormal state of the fire-resistors B_1 to B_4 .

If, for example, the fire-resistor B_1 is disconnected or grounded, namely, is in an abnormal state, and the others are in good condition, a pulse signal does not appear at the connection point P_7 even if a pulse signal is applied to the first common terminal P_1 . Therefore, to the input terminals of the detector A_2 only the pulse signals transmitted through the output terminal of the pulse generator PG and the connection points P_8 , P_9 , and P_{10} are applied and a pulse signal does not appear at the output terminal of the detector A_2 since the detector comprises an "AND" circuit. In this case the alarm or warning circuit may be set to operate, whereby failure of the fire-resistor can be detected.

In the present embodiment it should be noted that, although a certain pulse signal is transmitted to the common terminal P_2 through the diodes D_6 to D_8 , this pulse signal is not transmitted to the connection point P_7 since the diode D_5 is connected in a backward direction with respect to such a pulse signal. In other words, the connection point P_7 between the fire-resistor B_1 and the diode D_5 electrically isolates point P_7 against the pulse signals transmitted through the other fire-resistors B_2 to B_4 .

It will be easily understood that if all or any of the other fire-resistors B_2 to B_4 has failed, an output pulse does not appear at the output terminal of the detector A_2 in the same way as mentioned above.

It will be furthermore understood that even in the case wherein the diodes D_1 to D_4 are respectively connected to the fire resistors B_1 to B_4 as shown in FIG. 1, whether any of the diodes has failed can be checked in the same way.

Furthermore, it is necessary to check for failures of the circuits comprising the fire-resistors B_1 to B_4 and the diodes D_5 to D_8 , and attention is again directed to FIG. 1 and FIG. 2 with an explanation as follows.

Such a check can be effectively carried out by using the frequency dividers F_1 to F_4 and the detector A_1 .

During time t , between t_2 and t_3 , an output signal of the frequency divider F_1 is applied to the connection point P_3 and a pulse signal appears at the second common terminal P_2 unless the fire-resistor B_1 and the diode D_5 are defective. Since no pulse signal is transmitted from the pulse signal generator PG and the frequency divider F_2 to F_4 during the time period and the diode D_1 is connected in backward direction with respect to the pulse signal applied to the terminal P_3 , no pulse signal is transmitted to the terminal P_2 through the other circuits. No pulse signal is transmitted to the terminal P_2 , if the series circuit which comprises fire-resistor B_1 and the diode D_5 is defective, namely disconnected or shorted to ground. The pulse detector A_1 checks the signal from the frequency divider F_1 and the signal from the terminal P_2 . In the absence of the signal from the terminal P_2 , the alarm circuit may be set to operate in order to notify the abnormal state to the driver. Thus, the other circuits each comprising the fire-resistor of B_2 to B_4 and the diode of D_6 to D_8 are checked successively in the same way. As can be seen from the foregoing description, it should be noted that each of the terminals P_7 to P_{10} is electrically isolated by each of the diodes D_1 to D_4 , respectively, from the check signal transmitted through the other circuits.

The fire-resistors B_1 to B_4 might be checked by applying pulse signals to the terminals P_3 to P_6 and by detecting the pulse signals which are to appear at the terminals P_7 to P_{10} . However, where at least one of the diodes D_1 to D_8 is defective, the circuit does not operate since the diodes D_1 to D_8 are connected to the fire-resistors B_1 to B_4 in series.

As can be seen from the foregoing description in this embodiment the circuit line comprising the fire-resistor B_1 and the diode D_1 can be checked by applying a check signal to the terminal P_1 which is common to all the circuit lines and by detecting an output signal at the connecting terminal P_7 between the fire-resistor B_1 and the diode D_5 . Also, the circuit line of the fire-resistor B_1 and the diode D_5 can be checked by applying a check signal to the connecting terminal P_3 between the fire-resistor B_1 and the diode D_1 and by detecting an output signal at the other common terminal P_2 . Each circuit can be checked separately, since it is electrically isolated by the diodes from the check signal which is to be transmitted through the other circuits. Also, since the mean value of current which flows in the fire-resistors during checking is very small, it hardly occurs that the fire-resistors are set in operation by the check signal.

Although in the above embodiment, the frequency dividers F_1 to F_4 are employed in order to provide shifted pulse signals to each circuit, the invention is not limited thereto. Other circuit means which can provide predetermined check-signals, for example, pulse signal generators which can provide pulse signals having a predetermined waveforms and a predetermined interval can also be applied. Also, although the pulse detectors of this invention comprise AND circuit, other circuits such as NAND circuits etc. which can detect check signals can also be applied.

As described above, the present invention provides a failure check circuit system in a circuit comprising a plurality of circuit elements such as resistors for firing means connected in parallel between a first and a second common terminal wherein a plurality of diodes are connected respectively in series between the circuit elements and the second common terminal, a check signal is applied to the first common terminal, failure of the circuit elements is checked by detecting the output signals appearing at the connection points between the circuit elements and the diodes. The present invention further provides a failure check circuit system in a circuit having a plurality of serial unit circuits each comprising a first diode, a circuit element such as resistor used as a firing means and a second diode connected in parallel between a first and a second common terminal, wherein a check signal, such as a pulse signal, is applied to the first common terminal and the output signals appearing at the connection terminals between the circuit elements and the second diodes are detected, or wherein check signals such as pulse signals, are applied to the connection terminals between the first diodes and the circuit element and the output signals appearing at the second common terminal are detected.

According to the present invention, in a circuit comprising a plurality of circuit elements connected in parallel the existence of a failure in each unit circuit may be effectively checked and the mean value of signal current may be reduced by using a small signal such as a pulse signal, whereby misoperation of the firing means due to the signal current may be prevented. Fur-

thermore, in order to electrically isolate the signal paths in the unit circuits from each other the failure check circuit according to the present invention can be easily and simply constructed by using diodes only.

5 This invention may be applied not only to a failure check circuit system for an air-bag system for vehicles, but also to fire-alarm system, other firing means to simultaneously fire or blow-up many portions, etc.

10 While the invention has been described with reference to particular embodiments, this description is not meant to be construed in a limiting sense, but only illustrative of the principles involved. Various modifications of the embodiments described above will be apparent to persons skilled in the art upon reading this 15 specification.

We claim:

1. A failure check circuit comprising:
a plurality of unit circuits each comprising a resistor and a diode connected in series;
connection means for connecting said unit circuits in parallel between a first and a second common terminal;
means for supplying a check signal to said first common terminal; and
25 detecting means for detecting the existence of signals transmitted from said check signal supplying means to the connection points between said resistors and the diodes.

30 2. A failure check circuit according to claim 1, wherein said detecting means comprises a logic circuit and has a plurality of input terminals and an output terminal, said input terminals being respectively connected electrically to said connection points between said resistors and said diodes and to said first common terminal.

35 3. A failure check circuit comprising:
a plurality of serial unit circuits each comprising a first diode, a resistor and a second diode which are connected in series;
connection means for connecting said serial unit circuits in parallel between a first and a second common terminal, so as to directly connect said first and second diodes with said first and second common terminals, respectively;
means for supplying a first check signal to said first common terminal; and
50 means for detecting the signals transmitted from said check signal supplying means to the connection points between said resistors and said second diodes.

45 4. A failure check circuit according to claim 3, wherein said detecting means comprises a logic circuit and has a plurality of input terminals and an output terminal, said input terminals being electrically connected to said connection points between said resistors and said second diodes and to said first common terminal.

55 5. A failure check circuit according to claim 4, comprising a second means for supplying second check signals to the connection points between said first diodes and said resistors and a second detecting means for detecting the signal transmitted from said second means for supplying second check signals to said second common terminal.

60 6. A failure check circuit according to claim 5, wherein said second detecting means comprises a logic circuit and has a plurality of input terminals respec-

tively connected to said common terminal and to said connection points between said first diodes and said resistors.

7. A failure check circuit according to claim 6, wherein said second check signals comprise pulse signals shifted in time with respect to each other.

8. A failure check circuit according to claim 3, wherein said first check signal supplying means comprises means for generating a series of pulses.

9. A failure check circuit according to claim 5, wherein said means for supplying second check signals comprises a plurality of frequency dividers, the inputs of which are connected in common to the output of said first check signal supplying means and the respective outputs of which are connected to respective connection points between said first diodes and resistors.

10. A failure check circuit according to claim 9, wherein each of said frequency dividers has a different frequency division characteristic.

11. A failure check circuit according to claim 3, wherein each of said first and second diodes is con-

nected to pass current in the same direction between said first and second common terminals.

12. A failure check circuit according to claim 1, wherein said check signal is supplied to said first common terminal for checking the condition of said resistors.

13. A failure check circuit according to claim 3, wherein said check signal is supplied to said first common terminal for checking the condition of said resistors.

14. A failure check circuit according to claim 3, wherein said plurality of serial unit circuits serve for activating an occupant safety device of a vehicle, and said resistors of said unit circuits are firing resistors for activating the safety device.

15. A failure check circuit according to claim 5, wherein said plurality of unit circuits serve for activating an occupant protective safety device of a vehicle, and said resistor of said unit circuits are firing resistors for activating the occupant protective safety device.
